J. F. WILSON

SHIFT BAR FOR TYPEWRITING MACHINES

Filed Sept. 2, 1922

Patented Nov. 20, 1923.

1,474,751

UNITED STATES PATENT OFFICE.

JAMES FRANKLIN WILSON, OF KENSINGTON, MARYLAND.

SHIFT BAR FOR TYPEWRITING MACHINES.

Application filed September 2, 1922. Serial No. 535,936.

To all whom it may concern:

Be it known that I, JAMES FRANKLIN WILSON, a citizen of the United States, residing at Kensington, in the county of Montgomery and State of Maryland, have invented certain new and useful Improvements in Shift Bars for Typewriting Machines, of which the following is a specification.

This invention relates to certain new and useful improvements in typewriting machines, and it more particularly relates to that part of such machines known as the shift bars.

In recent years several of the large manufacturers of typewriting machines have put upon the market a model of a size and weight much smaller than the machines ordinarily used in business offices and which is adapted to be packed in a small case so as to be portable.

One of the machines of this kind upon the market is known as the "Underwood portable typewriter." This machine has three banks of keys, and adjacent to the frame on the left hand side opposite the banks of keys, there are two shift keys, one for the fingers or numerals, and one for the capital letters, and the case shifts are brought about by shifting the type bar hanger up and down by means of the shift keys.

The system of typewriting taught in most of the schools at the present day and especially to those who are blind or of defective eyesight, is known as the "touch system." Typewriting as taught by that system requires that each hand should cover one-half only of the key-board and that the fingers of neither hand should go beyond the portion assigned to it. In the Underwood typewriter the writing of such an address for instance as "Washington, D. C." requires the right hand to leave its position on the key-board and come over to the extreme left portion of that part assigned to the left hand in order to reach the shift key for the capital letters.

One of the objects of my invention, therefore, is to overcome this difficulty by providing a figure shift key and a capital letter shift key on the right hand side of the key-board.

Another object of my invention is to provide separable shift keys which may be readily attached to the frame of the machine as it is now upon the market; in

other words, this key shifting mechanism is so constructed as to be removably attached to the outer frame of the present machine. To persons of defective vision who are using the Underwood portable typewriter, my attachment has been found of great service as it gives them practically all of the advantages of the larger machine, and can be put on at slight cost.

A further object of my invention is to so construct the means or fastening plate whereby my device is attached to the frame that its adjustment may be somewhat varied so as to make a perfect adjustment.

A still further object of my invention is to provide a shift mechanism of the character described of great simplicity and durability both as a whole and in respect to each of its component parts so that its manufacture will be economically facilitated both as regards the production of parts and of their assembly.

With these and other objects in view which may be incident to my improvements, the invention consists in the parts and combinations to be hereinafter set forth and claimed, with the understanding that the several necessary elements comprising my invention may be varied in construction, proportions and arrangement, without departing from the spirit and scope of the appended claims.

In order to make my invention more clearly understood, I have shown in the accompanying drawings means for carrying the same into practical effect, without limiting the improvements in their useful applications to the particular constructions, which for the purpose of explanation, have been made the subject of illustration.

In the drawings:

Figure 1 is a perspective view of the right side of an Underwood portable typewriting machine, (part of the same being broken away) with my device attached;

Fig. 2 is a plan view of the bottom of the same part of the machine shown in Fig. 1;

Fig. 3 is a detail view of the numeral key bar shift with its contact finger;

Fig. 4 is a detail view of the fastening plate by means of which my device is secured to the outer frame of the machine;

Fig. 5 is a sectional view on the line 5—5 of Fig. 4;

Fig. 6 is a sectional view on the line 6—6 of Fig. 4, and Fig. 7 is a detail side view show-

ing the frame for lifting the carriage, the stop shift bar and the means for actuating said bar.

The numeral 1 represents the base of a typewriter case of a portable typewriter and the numeral 2 the frame of a typewriting machine with the usual type keys 3, ribbon spool 4, platen 5 mounted upon a carriage 6 adapted to travel back and forth upon a track 8 formed of a piece of bent sheet metal. These features, however, need not be further described as they form no part of my invention.

In the angular shaped end of said track 8, I fasten in place by a screw 9, or otherwise as may be desired, a metallic plug 11, whose outer end is threaded for the reception of the screw-threaded end of a bolt 12, upon which is mounted a small metallic 20 wheel or roller 13 adapted to freely revolve thereon.

Into the frame 2 of the machine are drilled two apertures and in them are fitted the screw-threaded bolts 14 (see Figs. 2, 4, 5) 25 which securely hold against the frame 2, the separable mounting plate 15 horizontally slotted at each end as clearly shown in Fig. 4, and having longitudinal ridges 15' across its face. The numeral 16 refers to two 30 vertically mounted plates, each provided with corresponding ridged or serrated faces, as seen in Fig. 5, so as to make more perfect the grip between the respective plates and provide against any slippage which otherwise might occur.

In the plate 15 is fixedly mounted one end of a stud shaft or pin 17, (see Fig. 6) the outer end of which is screw-threaded for the reception of a nut 18. Upon said stud shaft 17 is pivotally mounted the key-bar 20 having an upturned end or finger key 21 and the key-bar 22 having a like key 23, so that the bar may be readily manipulated by the operator.

Between the frame of the machine and the nut 18, I loosely mount upon the stud shaft 17, washers 24, 25 and 26, so as to space the key-bars and the farther ends 27 and 28 of said bars pass under the roller 13, and 50 when either is depressed by the operator said roller is slidingly and upwardly engaged thereby, the track 8 elevated, and with it the carriage travelling thereon.

The normal position of the type keys 55 upon the typewriter is such that pressure exerted upon them by the operator will cause the lower case letters, or what are usually called the small letters, to strike the platen. Upon pressure exerted, however, 60 on the upturned end 23 of the shift bar 22, the carriage is so lifted that upon the striking of any of the type keys by the operator the letters or symbols upon the center of the type bar will strike upon the platen 5.

65 It will be observed, however, that the inner

bar 20 has secured thereto by rivets 29 or otherwise (see Fig. 3) a depending arm 31 having a contact finger 32. Pressure when applied upon the upturned end of the bar 20 will cause the depending arm 31 carrying the contact finger 32 to swing so as to contact with the lower end 35 (see Fig. 7) of the stop shift bar 33, thereby throwing the upper end 37 of said bar away from its limiting position over the foot or projection 34 of the carriage lifting frame 36 and permitting the latter to be still further raised to what may be termed complete elevation, so that upon the striking of the type keys by the operator the letters or symbols upon the upper end of the type bar will strike upon the platen 5.

If the respective parts of my device were to be made by the company manufacturing the machine, it would not be difficult to find the exact center 37 and pierce the frame at that point. In order, however, to enable the device to be put upon the general market, I make the device as illustrated and any ordinary mechanic can drill the frame at 90 the appropriate points for the insertion of the bolts 14 and 14, and the point 17 can then be readily and exactly located by test and adjustment without the necessity of further drilling of the frame.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. An attachment for a typewriting machine having a shifttable platen and a stop shift bar, comprising a separable mounting plate to be secured to the frame of the machine; a stud shaft attached to the plate, and a shift lever fulcrumed thereon adapted to be applied to the exterior side frame of a typewriting machine, and means operated by said lever to shift the platen, of a finger depending from said lever and contacting the stop shift bar of said machine to elevate the platen when the lever is depressed.

2. In combination with a typewriting machine having a shifttable platen and a stop shift bar of a separable mounting plate, an attached stud shaft and a shift lever fulcrumed thereon adapted to be applied to the exterior of the side frame of a typewriting machine, a bar depending from said lever, a finger thereon contacting the stop shift bar of the machine to permit elevation of the platen, and means on said lever to elevate said platen when the lever is depressed.

3. The combination with a typewriter comprising a frame, a carriage, a platen thereon, a shiftable rail upon which said carriage is adapted to slide, and a stop shift bar which when actuated permits the elevation of the platen, a demountable plate adapted to be exteriorly applied to the side of a typewriter frame, and a shift lever pivotally mounted upon said plate, of a finger depending from said shift lever adapted to engage said stop shift bar upon the depression of the front end of the shift lever and elevate the platen to receive the impact of the upper case letters.
- 15 4. The combination with a typewriter comprising a frame, a carriage, a platen movably mounted thereon, a shiftable rail upon which said carriage is adapted to slide, and a stop shift bar which when actuated permits an elevation of the platen, a demountable plate adapted to be exteriorly applied to the side of the typewriter frame, a stud shaft extending from the plate and
- a shift lever fulcrumed thereon, of a finger depending from said shift lever adapted to engage said stop shift bar upon the depression of the shift lever and elevate the platen to receive the impact of the upper case letters.
- 25 5. The combination with a typewriter comprising a frame, a carriage, a platen movably mounted thereon, a shiftable rail upon which said carriage is adapted to slide, a separable mounting plate adapted to be applied to the exterior of the said frame of the typewriter, an attached stud shaft and a shift lever fulcrumed thereon, a bar depending from said lever, a stop shift bar normally holding said carriage against complete elevation, a finger on said depending bar contacting the stop shift bar to move it from the normal position and permit said lever to move said carriage to complete elevation.
- 30 40

In testimony whereof I affix my signature.
JAMES FRANKLIN WILSON.
